UNITED STATES PATENT OFFICE.

WILLIAM MARION HENSON, OF SAVOY, TEXAS.

AUTOMATIC LOCK FOR COTTON-GINS.

1,255,746.

Specification of Letters Patent. Patented Feb. 5, 1918.

Application filed March 6, 1917. Serial No. 152,858.

To all whom it may concern:

Be it known that I, WILLIAM MARION HENSON, a citizen of the United States, residing at Savoy, in the county of Fannin and

5 State of Texas, have invented a new and useful Automatic Lock for Cotton-Gins, of which the following is a specification.

This invention has reference to automatic locks for cotton gins, and its object is to 10 provide means whereby on raising the gin-stand breast it is automatically locked in the raised position, and accidents which frequently happen because of the falling of the gin stand breast are avoided.

15 It frequently happens in cotton gins that obstructing matters pass through with the cotton seed and it becomes necessary for the operator to raise the breast and place his hands within the same to remove such obstructions, this act being performed without 20 stopping the operation of the machine.

Should the breast accidentally fall while the operator has his hands beneath the breast to remove obstructions, injuries are caused to 25 the operator, which injuries are frequently of so serious a nature as to result in the loss of one or both hands, or one or both arms. Injuries of such character and from such cause are the most frequent in the operation 30 of cotton gins, and represent perhaps nine-tenths or more of all injuries which occur in the operation of cotton gins.

To raise the breast from its normal operative position to an extent to lift the grate 35 away from the saws, there is provided a rock shaft engaging the breast, which is hinged, and this rock shaft has an operating handle exterior to the gin.

The invention provides an automatic latch 40 having a constant tendency toward the latching position, but yieldable to the movement of the operating lever in a direction to lift the breast. As soon as the proper elevation is reached the latch snaps into the path of 45 the lever and holds the latter against return movement, so that an operator may clean the grate of obstructions without fear or liability of injury. When, however, the gin is freed from the obstruction the operator may 50 move the latch to the released position, whereupon the parts will gravitate into operative relation.

The invention will be best understood from a consideration of the following detailed description, taken in connection with the accompanying drawings forming part of this

specification, with the further understanding that while the drawings show a practical form of the invention, the latter is not confined to any strict conformity with the showing of the drawings, but may be changed and modified so long as such changes and modifications come within the scope of the appended claims.

In the drawings:

Figure 1 is a front elevation of a portion of a cotton gin stand showing the invention applied and with the breast raised.

Fig. 2 is an end elevation of the structure shown in Fig. 1.

Fig. 3 is a section on the line 3—3 of Fig. 1, but drawn on a larger scale.

Fig. 4 is a section on the line 4—4 of Fig. 1 but drawn on the scale of Fig. 3.

Fig. 5 is a section on the line 5—5 of Fig. 1 but drawn on a larger scale.

Referring to the drawings there is shown a portion of a cotton gin stand 1 which, being of known construction, needs no particular description. The stand is provided 80 with the usual breast 2 having a grate 3 in operative relation to gin saws 4 and having a hinge connection 5 so located that the breast may be rocked on the hinge to move the grate 3 away from a position where the 85 saws project through it to a position where the saws are back of the grate, and hence not liable to do injury to the hands of an operator introduced into the breast structure for removing obstructions therefrom.

Mounted in journal bearings 6 upon a cross bar 7 and upon one of the side posts 8 of the gin is a rock shaft 9 terminating at one end in an angle arm 10 and at the other end in an operating handle 11, both of which 90 may be in one piece with the shaft 9 or may be separately made therefrom and secured thereto. The arm 10 terminates in a finger portion 12 which may be rounded to engage against a wear plate 13 on what constitutes 95 the under surface of a bar 14^a extending across the lower end of the breast and sustaining the lower end of the grate 3, the breast hanging in a generally pendent position from the hinge means 5.

When the shaft 9 is rocked in one direction the arm 10 is so moved that the finger 12 is out of the path of the bar 14^a and the breast gravitates to its normal position in which the saws 4 project through the slots of the grate 3. When the shaft 9 is rocked in the other direction the finger 12, which is located

about midway of the breast, engages the plate 13^a and by a cam action rocks the breast so that the grate 3 is carried away from the saws 4, and the latter are no longer exposed through the grate. So long as the breast maintains the last-named position the operator may safely introduce his hands into the interior of the breast and remove any obstructions there lodged.

10 Mounted on the post 8 by means of a pivot pin 13, or in any other suitable manner is a lever 14 having at one end a handle 15, and at the other end an angle nose 16 in the path of which latter is a housing 17 made fast to the post 8. The lever 14 is movable about its pivot 13 to an extent to cause the nose end 16 to move into and out of the housing 17, but at no time far enough to escape from the housing, which latter may have an end 15 wall 18 in the path of the free end of the nose 16 to limit the movement of the lever in one direction. Connected to the handle end of the lever is one end of a spring 19 entering a casing 20 fast to the post 8, with the other end of the spring secured to the corresponding end of the casing. The tendency of the spring 19 is to rock the lever 14 in a direction to maintain the nose 16 in the path of the handle 11, but yieldable to permit rocking of the lever sufficiently to move the nose 16 out of the path of the handle 11. The spring 19 maintains the lever 14 normally in such position after the handle 11 has been raised that when the handle is depressed to elevate the breast the handle 11 will move along the lever until it passes below the nose portion 16, whereupon the latter is moved into the path of the handle 11 and thereby prevents any rising movement 25 thereof. The point on the nose 16 engaged by the handle 11 is on the opposite side of the vertical plane in which the pivot 13 is situated from the spring 19. The result is that any force which can be exerted upon the handle 11 to raise it and so permit the breast to fall is effectively resisted and consequently the locking of the breast in the elevated position is positive without, however, presenting any material resistance to the 30 movement of the lever 14 when purposely rocked to release the handle 11. While the

locking is certain, it is not of the positive nature which occurs when a dog or pawl engages behind a tooth.

The locking mechanism is of a nature resistant to accidentally applied forces to which it is liable to be subjected under conditions of use. For this reason the lock, while automatic in action in moving to the locking position, and movable without particular effort to the released position, is certain in action so that all liability of accident when clearing the breast from obstructions is obviated and the danger which has heretofore been encountered in the operation of cotton gins is eliminated.

What is claimed is:—

1. In combination with a member having a bent outer end at an angle thereto, a pivoted lever separate from the member and moving in a curved path at right angles to the bent outer end of said member, said lever having an operating handle at the upper end and having its lower end inwardly bent, and a spring for moving the lower end of the lever normally into the path of the bent outer end of the member, so as to cause said bent outer end of the member to wipe along the edge of the lever and become seated below the bent lower end of said lever.

2. In a cotton gin having a handled rock member for engaging and elevating the breast of the gin, a lever pivoted near one end and there provided with a handle, a controlling spring for the lever on the handle side of the pivot of the lever, and said lever having a nose at the other end at an angle to the length of the lever and movable into the path of the handle on the rock member for automatically locking the latter when the breast is in the elevated position, and a housing for the nose of the lever mounted on a fixed part of the gin.

In testimony, that I claim the foregoing as my own, I have hereto affixed my signature in the presence of two witnesses.

WILLIAM MARION HENSON.
